DESIGN FOR A CREMATORIAL URN

Thomas Briscoe, Seattle, Wash.

Application November 4, 1935, Serial No. 59,367

Term of patent 7 years

To all whom it may concern:

Be it known that I, Thomas Briscoe, a citizen of the United States, residing at Seattle, in the county of King and State of Washington, have invented a new, original, and ornamental Design for Crematory Urns, of which the following is a specification, reference being had to the accompanying drawing, forming part thereof.

Figure 1 is an elevation view of a crematory urn, showing my new design;

Figure 2 is a top plan view thereof; and Figure 3 is a perspective view thereof.

I claim:

The ornamental design for a crematory urn, as shown.

Signed at Seattle, this 25th day of October, 1935.

THOMAS BRISCOE.
